Application November 23, 1946, Serial No. 711,968

8 Claims. (Cl. 315—21)

1

The invention described and claimed herein relates to control means for cathode-ray tubes. More particularly, the invention provides automatic control means for correcting, substantially instantaneously, an unintended deviation in the position of the beam.

The present invention is of particular utility in television systems where it may be conveniently employed to correct an undesired departure of the spot of the scanning electron beam from a preselected path the beam is intended to follow. Control of this nature is particularly desirable in multi-color television systems employing a cathode-ray tube having a multi-color striped or mosaic-line screen, or in three-dimensional television systems employing a cathode-ray tube having differently polarized screen elements in striped arrangement, since deviation of the scanning spot from its intended scanning path introduces error in the picture being viewed which may be noticeable and objectionable.

In black and white television systems employing a conventional scanning pattern comprised of a plurality of vertically-displaced parallel lateral lines, the beam spot of the viewing tube may deviate vertically from its scanning path a limited amount without the effect of such deviation being noticeable to the observer. But in multi-color or stereoscopic television systems employing striped screens, considerably less vertical deviation is permissible before the error is noticeable. In short, for good quality of reproduction in these types of color and three-dimensional television systems, it is important that the spot of the scanning beam adhere closely to the line it is intended to scan. Apparatus which may be satisfactory for controlling the scanning of a black and white television tube may not be at all satisfactory for controlling the scanning of a multi-color or stereoscopic television tube because of the more rigid requirements of color and three-dimensional presentation.

It is an object of this invention to provide means for correcting, substantially instantaneously, unwanted deviations of a cathode-ray beam from a predetermined and desired condition with respect to its instantaneous position.

It is another object of this invention to provide means for maintaining a beam of electrified particles accurately positioned as it is deflected along a preselected path.

It is another object of this invention to provide means, responsive to an unwanted deviation of an electron scanning beam from substantially any portion of its scanning path, for generating correction signals, and for synchronizing the application of the correction signals with the scanning

2

cycle in such manner that the deviation is substantially corrected.

It is a more specific object of this invention to provide means in a television system for correcting, substantially instantaneously, unwanted vertical deviations of a cathode-ray beam from a preselected scanning pattern comprised of a plurality of vertically-displaced lateral scanning lines.

10 It is a still more specific object of this invention to provide scanning-beam control means adapted to function in a selective manner to maintain accuracy of beam position in a television system employing an interlaced scanning pattern.

These and other objects, features and advantages of the present invention will be clear from a consideration of the following detailed description taken in conjunction with the accompanying drawings, in which

Figure 1 is an illustration, partly schematic, partly diagrammatic, of a cathode-ray tube and associated circuit employing one embodiment of the invention;

25 Figure 2 is an illustration of a cathode-ray tube employing an alternate arrangement of control elements;

Figure 3 is a schematic representation of an arrangement of control elements which may be employed with the cathode-ray tubes of Figures 1 and 2;

30 Figure 4 is another arrangement of control elements which may be used in certain applications; and

35 Figure 5 is a schematic representation of a spiral-scan control means.

Referring now to Figure 1, there is illustrated a cathode-ray system in which conventional circuits and well known tube elements are merely

40 shown in block form. The system is shown as comprising a source of horizontal deflection signals 10, a source of vertical deflection signals 11, amplifiers 13 and 14 for the horizontal and vertical deflection signals respectively, a voltage adder 15, and a cathode-ray tube 16 having conventional cathode 17, control grid 18, horizontal deflecting means 19, vertical deflecting means 20, and beam 21. The screen 22 and control elements 23 are described in detail later.

45 50 Vertical deflection signals from source 11 are applied by way of voltage adder 15 and amplifier 14 to vertical deflecting means 20, and horizontal deflecting signals from source 10 are applied through amplifier 13 to horizontal deflecting means 19.

Cathode-ray tube 16 may serve as the viewing tube of a television receiver, or as the camera

tube of a television transmitter, or may serve other cathode-ray tube functions. For the purpose of facilitating the description of the present invention, cathode ray tube 16 is assumed to be the viewing tube of a three-color television receiver having video and blanking signals from source 12 applied to control grid 18. Screen 22 is assumed to be comprised of different fluorescent phosphors arranged in closely-spaced, parallel, lateral lines; adjacent lines are comprised of different phosphors, but every third line is comprised of the same phosphor. Or, alternatively, screen 22 may be comprised of a common fluorescent material, as for example, a white phosphor, to one surface of which color filter material has been applied in closely-spaced, narrow, lateral strips or lines, adjacent strips being different color filters and every third strip being the same color filter.

In Figure 1, the positions of nine lateral lines of fluorescent screen 22 are shown. These are identified by reference letters *a* to *i* inclusive, and they are intended to be illustrative of the much larger number of lines of which the fluorescent screen of an actual three-color television viewing tube will be comprised.

In accordance with the present invention, control means 23 are associated with screen 22 to provide accuracy of movement of the scanning beam 21. In one embodiment, illustrated in Figure 1, control means 23 comprises a plurality of closely-spaced, mutually-insulated, conductive strips mounted within the tube between the source of the beam 21 and fluorescent screen 22, one control strip being provided for each scanning-line of the fluorescent screen. The conductive control strips are porous to electrons and may be comprised, for example, of a very thin coating of aluminum or silver which may be conveniently applied directly to the surface of the fluorescent screen, as by a suitable evaporation process. In such a process, a suitable stencil or mask may be employed to control the character or configuration of the metal deposit. In the instant embodiment, the configuration is that of a plurality of closely-spaced, vertically-displaced, lateral strips.

In another embodiment of the invention, illustrated schematically in Figure 2, the conductive control strips 63 are applied to the glass face of the cathode-ray tube, and the phosphor of the fluorescent screen is deposited upon the control strips. In this case, the phosphor material 62 is between the electron beam source 57 and control strips 63; hence the phosphor is thinly applied so as to permit a sufficient number of electrons to pass completely therethrough and strike the control strips. If control strips 63 be located between the phosphor material and the eye 64 of a viewer positioned in front of the tube, the control strips are comprised of a very thin application, as for example a thin application of silver, in order to be transparent to light. If the method of image presentation be such that the screen is viewed from the rear, then of course the control strips need not be transparent to light.

Referring now to Figure 3, there is illustrated a schematic plan view of the physical arrangement and electrical connections of the conductive control strips as employed in both of the embodiments described above and illustrated in Figures 1 and 2. The plan view of the control strips is the same irrespective of whether the strips are located in front of, or in back of, the fluorescent screen. In Figure 3, eleven control strips, *a*' to *i*'

inclusive, and *aa'* and *ii'*, are shown and these are intended to be representative of the large number of control strips which will ordinarily be associated with the fluorescent screen. The actual number of control strips is preferably larger by two than the number of scanning lines in the pattern. In Figures 1, 2 and 3, nine of the control strips shown, i. e., strips *a'* to *i'* inclusive, correspond to the nine scanning lines, *a* to *i* inclusive, of fluorescent screens 22 and 62 shown in Figures 1 and 2, respectively. The other two strips, *aa'* and *ii'*, are extra control strips, one being provided at the top of the screen and the other at the bottom of the screen. Where the control strips are comprised of thin applications of metal, deposited as by an evaporation process, the extra strips may either be deposited directly upon the glass face of the tube, or additional phosphor may be provided to serve as a backing for the metal deposit.

All of the control strips are shown as having a slight downward slope to the right; this corresponds with the customary slope of the scanning lines of fluorescent screens, it being understood that the customary scanning action is from left to right across the image and downward.

Every third control strip is shown to be electrically connected to a common lead, thus forming three groups of interlaced control elements. The individual connections from the control strips to the common leads, and also portions of the common leads, may conveniently be comprised of very fine lines of metal deposited by suitable evaporation process.

In Figures 1, 2 and 3 of the drawings, a group comprising control strips *a'*, *d'*, *g'* and *ii'* are shown connected to common lead R; a second group comprising strips *b'*, *e'* and *h'* are shown connected to common lead B; and a third group comprising strips *aa'*, *c'*, *f'* and *i'* are shown connected to common lead G. The control strips connected to lead R may be deemed to be associated with the lines of screen 22 which under electron bombardment emit a red color, either as a result of the employment of a red filter or of the employment of a red phosphor. Similarly, the control strips connected to leads B and G may be considered as being associated with blue and green lines, respectively, of screen 22.

Referring again to Figure 1, a suitable positive potential is applied to each of the control strips by way of the common leads R, B, G and resistors 24, 25, 26 respectively. Capacitor 56 is a by-pass capacitor. Each of the three leads, R, B and G, is connected to suitable switching means 30, through which control signals are passed to feedback connections 31 and 32. The control signals referred to are derived from the impingement of electrons of beam 21 upon one of the conductive control strips. For as the impinging electrons return to cathode through one of the resistors 24, 25, 26, a signal is developed at the ungrounded end of the resistor which is available for control purposes.

In order to effectuate the desired control, the switching means provided in the present illustration are adapted to accomplish the following: (a) provide an open circuit between each of the feedback connections 31, 32 and the control strip associated with the line intended to be scanned; (b) provide a closed circuit between one feedback connection and the control strip associated with the line adjacent and above the line intended to be scanned; (c) provide a closed circuit between 75 the other feedback connection and the control

strip associated with the line adjacent and below the line intended to be scanned.

The switching means for accomplishing the above may be of any suitable form, preferably electronic. However, for the purpose of describing the instant embodiment, it will suffice to illustrate and describe a mechanical switching arrangement. There is accordingly shown in Figure 1, a pair of rotary-type switches 33 and 34, having rotatable switch arms 35, 36 respectively, and each having three arcuate contact segments L, M, N and L', M', N' respectively. Each of the three common leads R, B and G, is connected to one of the three segments of each switch. In the illustration, lead R is connected to segments L and L', lead B is connected to segments M and M', and lead G is connected to segments N and N'.

Switch arms 35, 36 are ganged together and are rotated clockwise simultaneously, as by a synchronous motor (not shown), with switch arm 35 lagging switch arm 36 by one segment. The leads of feedback connections 31 and 32 extend from switch arms 35 and 36 to amplifiers 37 and 38, respectively. These amplifiers are preferably D.-C. amplifiers so that the D.-C. component of the correction voltage may be preserved. Or, alternatively, means may be included in amplifiers 37, 38 for accomplishing D.-C. insertion.

In the illustrated embodiment now being described, the output signals from amplifier 38 are shown to be inverted in phase inverter 41, but if desired, the inversion of the signal may of course be accomplished by having amplifier 38 comprise one more, or one less, stage than amplifier 37. The output signals of amplifier 37 and the inverted signals of amplifier 38 are combined in voltage adder 39 and are applied, by way of common connection 40 and switch S, to voltage adder 15 where they are combined with the vertical deflection signals from source 11.

If desired, the control signals fed back by way of connections 31 and 32 may be applied respectively to opposing plates of the vertical deflecting means, in which case inversion of the signals of one of the paths, is unnecessary.

The operation of the embodiment of our invention illustrated in Figure 1 will now be described. Beam 21 of tube 16 is moved through a predetermined scanning pattern, as by the application of horizontal and vertical deflecting signals from sources 10 and 11 to the horizontal and vertical deflecting means 19 and 20 respectively.

Assume an instant in the scanning pattern when beam 21 is scanning a blue line as, for example, line b. A portion of the electrons of beam 21 completely penetrate control strip b' and impinge upon the phosphor of line b causing it to glow. The remainder of the beam electrons partially penetrate strip b'. Observe that strip b' is connected to common lead B and that lead B is connected to segment M of switch 33 and segment M' of switch 34. Assume now that an unavoidable departure occurs in one or more of the potentials determining or influencing vertical deflection, thus causing beam 21 to deviate in a downward direction from its intended position. In so deviating, some or all of the electrons of beam 21 impinge upon control strip c'; some of these impinging electrons penetrate through strip c', while others penetrate but partially therethrough. Those electrons which impinge upon, but only partially penetrate through, strip c', return to cathode through resistor 26, and a signal is thereby developed across the resistor.

Observe that control strip c' is connected to common lead G and that lead G is connected to segment N of switch 33. Rotating switch arm 35 of switch 33 is in contact with segment N and the signal produced across resistor 26 is applied by way of connection 31 to the input circuit of amplifier 37. The voltage developed across the output circuit of amplifier 37 is applied by way of voltage adder 39 and lead 40 to voltage adder 15 where it is combined with the vertical deflecting signals from source 11. The gain and phase characteristics of the feedback circuit are so arranged and adjusted that the polarity and magnitude of the voltage delivered by amplifier 37 is effective to move beam 21 in an upward direction. If desired, the gain and time-delay of the feedback amplifier 37 may be so adjusted that the upward correcting movement of beam 21 is sufficient to cause the beam to overshoot control strip b', whereupon a portion of the electrons strike control strip a' which is adjacent and above.

It will be observed that when beam 21 deviates downwardly from control strip b' to c', no correction signal is obtained from amplifier 38 for the reason that connection 32 is open at switch 34, switch arm 36 being out of contact with segment N'.

It should be mentioned here that the frequency-response characteristics of amplifiers 37 and 38 are preferably such that steep wave-front control signals may be passed therethrough, thus permitting the control voltages to reach voltage adder 15 with a minimum of delay.

The correction signal derived is of course a function of the number of electrons impinging upon, but not completely penetrating through, an adjacent control strip. If beam 21 is intensity-modulated, as will ordinarily be the case, then the system preferably is so adjusted that a beam of strong intensity is prevented, by the action of the control signal, from impinging upon an adjacent control strip except for a very small portion of the beam-spot area. However, when the beam is modulated from strong intensity to a weaker intensity, a greater portion of the beam-spot area tends to encroach upon the adjacent control strip. For optimum operation, the system may be so arranged that amplifiers 37 and 38, in addition to having a steep frequency-response characteristic, provide high gain, so that adequate values of control voltage may be derived from the impingement of a relatively small number of electrons upon the adjacent control strips. In other words, in accordance with the method of operation now being described, a given departure of deflection-voltage causes a beam of strong intensity to encroach upon an adjacent control strip by an extremely small portion of its spot area, while a weaker beam encroaches by a larger, but, tolerable, amount.

An alternate method of compensating for the intensity-modulation of the beam is to apply the video signals from source 12 exclusive of the blanking signals, as by way of video selector 60 and connection 61, to amplifiers 37 and 38 to control the gains of the amplifiers so that, when the beam intensity is low, the amplifier gain is high, thereby maintaining the gain around the feedback loop independent of beam intensity, and thus maintaining the controlled spot-position substantially independent of beam intensity.

Referring again to Figure 1, assume now that beam 21 has deviated upwardly from line b, either as a result of an overshooting control voltage as mentioned above, or as a result of an

unavoidable departure in one or more of the voltages determining vertical deflection. When an upward deviation from line position *b* occurs, electrons from beam 21 strike control strip *a'*. Some of the impinging electrons penetrate completely through the strip. Other electrons only partially penetrate strip *a'* and in returning to cathode 17 these electrons produce a signal across resistor 24 to which strip *a'* is connected by means of common lead *R*. It will be seen that lead 10 and *R* is connected to segment *L* of switch 33 and segment *L'* of switch 34. Switch arm 35 of switch 33 is not in contact with segment *L* and feedback connection 31 is consequently open at switch 33. Switch arm 36 of switch 34 is, however, in contact with segment *L'* and the voltage produced across resistor 24 is applied across the input circuit of amplifier 38. The output signals of amplifier 38 are inverted, as by means of phase inverter 41, and the signal is then applied to voltage adder 15 by way of voltage adder 39 and connection 40. The effect of combining the inverted signals from amplifier 38 with the vertical deflection signals from source 11 is to move beam 21 in a downward direction. If desired, the gain and time-delay of amplifier 38 may be so adjusted that the downward correcting movement of beam 21 is sufficient to cause the beam to overshoot control strip *b'*, whereupon a portion of the electrons strike control strip *c'*. If the system be arranged and adjusted to employ overshooting control, then the beam, following an unwanted departure, is given an oscillatory motion for the remainder of the scanning line whose frequency is preferably higher than that of the picture elements, and amplifiers 37 and 38 are peaked amplifiers adapted to pass the oscillatory frequency, as well as lower frequencies.

Referring again to Figure 1, it will be observed that when line *b* is being scanned, the voltage developed across resistor 25, as a result of electrons impinging upon control strip *b'* and returning to cathode by way of lead *B*, is not applied to voltage adder 15 for the reason that both feedback circuits 31 and 32 are open at segments *M* and *M'* of switches 33 and 34, respectively. It will be understood that the angular positions occupied by switch arms 35 and 36 in Figure 1 of the drawings assume that line *b*, or a line of 50 the same field as *b*, is being scanned.

In order to effectuate the switching which my novel arrangement requires, switch arms 35, 36 are rotated in coordination with the movement of scanning beam 21, the rotating speed of the 55 switch arms being dependent upon the scanning pattern being employed. For example, in a three-color system employing an every-third-line interlaced scanning pattern, switch arms 35 and 36 of switches 33 and 34 are rotated clockwise, and are so timed as to remain in engagement with each switch segment during the scanning of a field, i. e. during the scanning of the lines common to a single color. For example, arm 35 engages segment *N* and arm 36 engages segment *L'* at the instant that beam 21 starts to sweep line *b*. Beam 21 completes scanning of the color field, of which line *b* is a component, at the same instant that rotating arms 35, 36 complete their respective passages over switch segments *N* and *L'*, respectively. During the period required for beam 21 to return to line *c* at the top of the screen, switch arms 35, 36 traverse the spaces between switch segments *N*, 70 *L* and *L'*, *M'*, respectively.

As beam 21 scans the next color field, the uppermost line of which is *c*, the arrangement shown in Figure 1 continues to be effective to provide vertical deflection control similar to that just described in connection with the preceding field. This may be readily confirmed by an examination of the circuit arrangement of Figure 1, and a detailed description thereof is not believed to be necessary.

The control system illustrated in Figure 1 and described above, is also applicable to television systems employing every-other-line interlace scanning, or every-line sequential scanning.

Where every-other-line interlace scanning is to be used with the arrangement illustrated in Figure 1, every third control strip may be connected to a common lead, just as in the case of every-third-line interlace scanning described above, but if this be done switch elements 35, 36 should be rotated counterclockwise instead of clockwise, and the speed of rotation should be such that elements 35, 36 sweep over a switch segment during the time required to scan a single line position. This requires a very high rotary speed, well beyond the capabilities of most mechanical switches, but well within the capabilities of an electronic switching device, as for example, a radial-beam tube. The switching arrangement shown schematically in Figure 1 and thus far referred to in mechanical terms, may be deemed to be also a schematic representation of a radial-beam tube in which elements *L*, *M*, *N* and *L'*, *M'*, *N'*, represent separate anodes arranged in circular fashion about cathodes 27 and 28 respectively, and in which rotating elements 35 and 36 represent beams of electrons which are rotated about the axes of the tubes in known manner, as by the application of a rotating magnetic and/or electric field.

Assume now a system as described in the above paragraph, i. e., having an every-other-line interlace scanning pattern and radial-beam tube switches, the beams of which rotate counterclockwise at a speed of one anode for each line scan. Then it may be readily determined from an examination of the circuit of Figure 1, that the voltage developed across the resistor corresponding to the line intended to be scanned, is not fed back to the voltage adder 15 because of the fact that both feedback circuits 31, 32 are open at the switches. However, for a downward deviation, it will be observed that a correcting signal is fed back by way of connection 31 and amplifier 37, while for an upward deviation, a correcting signal of opposite polarity is fed back by way of connection 32, amplifier 38 and phase inverter 41.

If the control-strip pattern and switching arrangement shown in Figure 1 be employed when the scanning pattern requires that every line be scanned in sequence, then radial-beam tubes are preferably employed as switches, and the beams represented by switch elements 35, 36, should be rotated clockwise at a speed of one anode for each line scanned. If this be done, then control is obtained in a manner similar to that described above for every-third-line and every-other-line scanning.

It is to be understood that our invention is not limited to the specific pattern of interlaced control strips illustrated in Figures 1, 2 and 3. Other control strip arrangements may of course be used. For example, where an every-other-line interlace scanning pattern is to be employed the

control means may conveniently take the form shown in Figure 4.

In the arrangement shown in Figure 4 only two groups of control strips are employed. The strips may be in the form of very fine wires positioned along opposite lengthwise edges of the path which the beam is intended to follow, as for example, in the interstices of the scanning lines of the screen of a stripped multi-color viewing tube. The control wires may, if desired, be applied by a suitable evaporation process. Assume that the arrangement shown in Figure 4 is representative of a screen in which dotted line *ab* represents the first line to be scanned. Control wire *aa* runs along the upper lengthwise edge of the scanning line and control wire *bb* runs along the lower lengthwise edge. If desired, the spot of the scanning beam may be of such size that when properly centered upon scanning line *ab* some of the electrons impinge upon control wire *aa* and a substantially equal number impinge upon control wire *bb*, thereby generating control voltages of equal magnitude in the two control wires. These equal voltages are fed back by way of connections 31 and 32 and are applied in opposition, as by the means shown in Figure 1, to maintain the beam spot substantially centered between the two control wires. Upon the completion of the scanning of line *ab*, line *cd* is next scanned, and control is effectuated by means of control wires *cc* and *dd*, in a manner similar to that just described. Upon completion of the scanning of a field comprised of alternate lines, the beam is returned to the top of the screen. The first line to be scanned in the new field is that represented by the dot and dash line *bc*, and control is accomplished by means of wires *bb* and *cc*.

With the arrangement of Figure 4, switching is only necessary at the end of each field; hence a pair of two-segment rotary type mechanical switches 51, 52 driven at a speed of one revolution per scanning frame are satisfactory.

It is also to be understood that our control system is not limited to scanning patterns in which the lines to be scanned are horizontal, or substantially horizontal, i. e. having the customary slight downward slope. On the contrary, our system will operate quite satisfactorily with scanning patterns of various configurations, as for example, with a spiral scanning pattern. As will be understood by those skilled in the art, a spiral scanning pattern may be obtained by amplitude-modulating horizontal and vertical deflection signals which are sinusoidal and 90° out of phase. If it be assumed that the horizontal deflection signals provided by source 10 of Figure 1 are 90° out of phase with the vertical deflection signals provided by source 11, and that both be sinusoidal, then the modulation necessary for spiral scanning may be provided by applying a saw-tooth voltage from generator 42 by way of switch *W* and voltage adder 43, to horizontal and vertical amplifiers 13, 14, so as to control the gain thereof. The control voltages fed back by way of lead 40 may then be applied by way of switch *S* to the voltage adder 43 to control the accuracy of the radial deflection.

For the control of spiral scanning, two control strips of spiral configuration may be employed, as is illustrated in Figure 5. The space between the strips defines the path the beam is intended to follow. If the beam deviates outwardly, electrons impinge upon control strip *r*, and the voltage developed across resistor 49 is fed back, as through connection 31 of Figure 1, amplifier 37, 75

voltage adder 39, conductor 40, and switch *S*, and is applied to voltage adder 43 to alter the saw-tooth wave in desired manner. Similarly, if the beam deviates inwardly, electrons impinge upon target strip *t*, and the voltage developed across resistor 50 is fed back, as through connection 32 of Figure 1, amplifier 38, phase inverter 41, voltage adder 39, conductor 40 and switch *S*, and is applied to voltage adder 43. No switching means is required in the spiral scanning arrangement just described. It should also be mentioned that, if desired, the saw-tooth generator 42 may be omitted, and the control voltages developed by the impingement of electrons upon strips *r* and *t* may be relied upon to maintain the scanning beam in its intended path between the control strips.

Thus far our description of the invention has indicated that control strips are provided along both lengthwise edges of the path the beam is intended to follow, thus providing positive control against unwanted deviations in either of two opposing directions.

If desired, control elements may be provided along one edge only of the preselected path of the beam. In that event, and assuming lateral scanning, the vertical deflection signal may be biased to such an extent that, in the absence of the correction signal, the beam departs from its intended path by a predetermined amount in the direction of the control element associated therewith, and electrons which thereupon impinge upon the control strip are utilized to develop a correction voltage of sufficient magnitude to substantially overcome the bias. Hence, in the absence of voltage deviations, the beam follows its intended path.

The magnitude of the bias referred to above, may be substantially equal to the maximum deflection-voltage deviations, of opposite sign to the bias, which are anticipated. Such deviations, when they occur, merely tend to overcome, or at least diminish, the bias and thus cause the beam to withdraw, at least partially, from the control strip, thereby diminishing the correction signal developed. The net result is that the beam remains substantially in its proper vertical position.

When voltage deviations of the same sign as the bias occur, the beam tends to invade the control strip by an increased amount and correction signals of increased magnitude are developed which are effective to overcome substantially the said voltage deviations of same sign.

Suitable switching and feedback means for the biased system above described are provided by switch 33, feedback path 31, amplifier 37, etc., of the circuit illustrated in Figure 1, it being understood that only one switch and one feedback circuit are required for the biased system.

Control means which employ a second electron beam to accomplish results similar to those of the instant invention are described and claimed in a copending application of one of us, namely, 65 Allen C. Munster, filed Nov. 23, 1946, Serial No. 711,969, and assigned to Philco Corporation. Certain advantages over the instant invention, and also some disadvantages, are obtained from the employment of a second beam, as will become clear from a reading of the aforesaid copending application.

Beam control means, satisfactory for certain applications, as for example, where scanning of a plurality of interlaced parallel lines is not involved, are described in copending application of

the other of us, namely, David E. Sunstein, filed July 24, 1945, Serial No. 606,773, assigned to Philco Corporation.

We have described several embodiments of our invention. Other embodiments, not requiring invention, will occur to those skilled in the art.

Having described our invention, we claim:

1. In an electrical system: means for generating a beam of electrified particles; means for cyclically deflecting said beam successively along a plurality of preselected scanning lines; means responsive to deviations of said beam for generating signals identifiable with the direction of said deviations, said signals being derived from the change in the electrical potential of a scanning line which is impinged by said beam in deviated position; means for selecting said signals in synchronism with said beam deflection; and means for applying said selected signals to said beam in such manner as to oppose said deviations.

2. In an electrical system: means for producing a beam of electrified particles; a first means for cyclically deflecting said beam in one coordinate; a second means for cyclically deflecting said beam in a second coordinate; a target plate of pre-selected configuration; means responsive to changes in the electrical potential of said target plate resulting from bombardment thereof by a beam which has deviated from its intended position in said second coordinate; and means for selectively coupling portions of said responsive means to said second deflecting means in synchronism with the cyclical movements of said beam.

3. In a cathode-ray system: a screen; means for producing a cathode-ray beam; means for cyclically moving said beam across said screen in successive lines in accordance with a preselected scanning pattern; control elements of conductive material so positioned that during successive portions of said scanning cycle each of said elements is successively positioned substantially parallel with and adjacent to one side of a line then being scanned, and during other successive portions of said scanning cycle each of the same said elements is successively positioned substantially parallel with and adjacent to the other side of a different line then being scanned; means responsive to changes in the electrical potential of said control elements for deriving control signals from the bombardment of said adjacent control elements; and means synchronized with said scanning cycle for utilizing the signal derived from an element adjacent the line then being scanned to move said beam toward said last-named line.

4. In a television system; a screen; means for producing an electron beam; means for cyclically scanning said screen with said beam in accordance with a preselected scanning pattern comprised of a plurality of interlaced fields; a plurality of control elements corresponding to said scanning fields; means responsive to changes in the electrical potential of said control elements for deriving signals from the bombardment of said control elements by said beam; means synchronized with said scanning operation for disregarding signals derived from the bombardment of an element corresponding to the field then intended to be scanned, and for utilizing signals derived from the bombardment of elements corresponding to a field not intended to be then scanned, to return said beam to its intended field.

5. In a television system; means for generat-

ing an electron beam; means for cyclically deflecting said beam in a plurality of successive scanning fields in accordance with a preselected scanning pattern; a first group of control elements positioned to be bombarded by electrons of said beam in the event said beam departs in a first direction from a first field and in a second direction from a second field; a second group of control elements positioned to be bombarded by electrons of said beam in the event said beam departs in said second direction from said first field and in said first direction from said second field; means for deriving control voltages from the changes in the electrical potential of said control elements resulting from bombardment thereof by said beam; and means synchronized with said deflection cycle for utilizing said control voltages to oppose departure of said beam from the fields of said preselected scanning pattern.

6. In a television system; a screen; means for producing an electron beam; means for cyclically scanning said screen with said beam in accordance with a preselected scanning pattern comprised of a plurality of interlaced fields; control strips of conductive material positioned in the interstices of said scanning lines; means for deriving control signals from the changes in electrical potential of said control strips resulting from the bombardment thereof by said scanning beam; means synchronized with the scanning motion of said beam for utilizing signals derived from a control strip when said strip is adjacent one side of a line then being scanned to move said beam toward said line; and means synchronized with the scanning motion of said beam for utilizing the signals derived from said same control strip when said strip is adjacent the other side of a different line then being scanned to move said beam toward said different line.

7. In an electrical system: means for generating a beam of electrified particles; means for cyclically deflecting said beam successively along a plurality of preselected scanning lines; means responsive to changes in the electrical potential of said scanning lines caused by deviations of said beam for generating correcting voltages; and means for simultaneously coupling different portions of said responsive means to said deflection means successively in synchronism with said deflection cycle to so modify the operation of said deflection means as to oppose said deviations.

8. In an electrical system: means for generating a beam of electrified particles; means for cyclically deflecting said beam successively along a plurality of preselected scanning lines; means responsive to deviations of said beam for deriving control signals from changes in the electrical potential of said scanning lines resulting from impingement thereupon of electrons of said beam when in deviated position; and means synchronized with said beam deflections for coupling different portions of said responsive means differently and successively to said beam-deflection means so as to oppose said deviations.
